UNITED STATES PATENT OFFICE

155,266

DESIGN FOR AN AUTOMOBILE

Curt Bretschneider, Philadelphia, Pa.

Application December 6, 1947, Serial No. 143,013

Term of patent 7 years

(Cl. D14—3)

To all whom it may concern:

Be it known that I, Curt Bretschneider, a citizen of the United States, residing at Philadelphia, in the county of Philadelphia and State of Pennsylvania, have invented a new, original, and ornamental Design for Automobiles, of which the following is a specification, reference being had to the accompanying drawing, forming a part thereof.

In the drawing, Figure 1 is a side elevation; Figure 2 a top plan view; Figure 3 a bottom plan view; and Figure 4 a front elevation of an automobile, showing my new design.

I claim:

The ornamental design for an automobile, as shown.

CURT BRETSCHNEIDER.
